UNITED STATES PATENT OFFICE.

WILLIAM L. BARRON, OF NEWARK, NEW JERSEY, ASSIGNOR TO THE SINGER MANUFACTURING COMPANY, A CORPORATION OF NEW JERSEY.

BUTTON-SEWING MACHINE.

Application filed September 25, 1918. Serial No. 255,691.

To all whom it may concern:

Be it known that I, WILLIAM L. BARRON, a citizen of the United States, residing at Newark, in the county of Essex and State 5 of New Jersey, have invented certain new and useful Improvements in Button-Sewing Machines, of which the following is a specification, reference being had therein to the accompanying drawings.

10 My invention relates to a new and improved means for sewing on buttons.

One of the objects of the invention is to provide a compact, simple and inexpensive machine for tacking, sewing on buttons, etc., 15 more particularly designed for use in laundries and other places where a machine may not be in continuous use and is required to be readily adjustable for sewing two or four-hole buttons of various sizes.

20 Another object is to provide means for varying the jogging and shifting movement of the work-holder, each of which means is self-centering with respect to the needle, permits of a very fine adjustment and requires no tools for the adjustment.

25 A further object is to support the work-holder independently of the cloth-plate, to allow of the ready removal of the latter.

The invention is embodied in a machine 30 which comprises the usual overhanging arm and head carrying a needle and its actuating means, a cloth-plate and a loop-taking means below the cloth-plate. A bracket projects upwardly from the base, and vertically 35 mounted in spaced ears on the bracket and outside the periphery of the cloth-plate is a shaft which carries above the cloth-plate a work-holder of the general character shown in my prior Patent No. 1,093,241, 40 dated April 14, 1914. The button-clamp or button-positioning means of the work-holder is not rigidly secured to the holder, however, but is slidably mounted on a bar which is pivoted on a horizontal axis to the 45 work-holder. Any desired button-positioning means may be used instead of the one shown, as this forms no part of the present invention. A lever fulcrumed on said bar is connected to the button-clamp on one 50 side of its fulcrum, and spaced stops on the button-clamp limit the movement of the lever. A wedge-shaped part is adjustably mounted on the lever between said stops to vary the throw of said lever and maintain

the extremes of shifting movement of the 55 button-clamp central with respect to the needle. Secured to the vertical shaft between the ears on the lug is a split collar formed on a slotted arm. A slide-block is 60 adjustably secured to said arm and a link 65 is secured to said block and is connected at its other end to a feed-rocker, one end of which rocker is journaled on the bracket and the other end of which is actuated by a cam having a one-to-two gear connection 70 with the main-shaft. The lateral oscillation or jogging of the work-holder may be varied by changing the position of the slide-block. The segmental slot in the arm, through 75 which the bolt carried by the link projects, has its center of curvature at the opposite pivotal point of the link. By this construction the needle always remains centrally disposed with respect to the extremes of movement of the work-holder, no matter how 80 these extremes are adjusted.

Referring to the accompanying drawings, Fig. 1 is a side elevation of the machine. Fig. 2 is a front elevation. Fig. 3 is a top plan view of the work-holder. Fig. 4 is a 85 horizontal section taken through the axis of the main-shaft. Fig. 5 is a rear side elevation of the work-holder and its mounting. Fig. 6 is a bottom plan view of the work-holder. Fig. 7 is a vertical longitudinal 90 section through the adjusting lever of the button-clamp. Fig. 8 is a bottom plan view of the means for varying the jogging movement of the work-holder. Fig. 9 is a section on the line 9—9 of Fig. 8. Fig. 10 is a section on the line 10—10 of Fig. 3. Fig. 11 is an end view of the spool-holder and its support. Fig. 12 is a top plan view of the hinged spool-support, and Fig. 13 is a development of the actuating cam.

In the drawings 1 is the base of a machine having the overhanging arm 2 and head 3. The needle 4 is secured to a needle-bar 5 driven by a rock-shaft 6 connected to a pitman 7 driven by a crank 8 on the main-shaft 9. A cloth-plate 10 is removably secured to the base, as by screws or in any other desired manner. A looper 11 is mounted on the main-shaft. A bracket 12 is secured to the base and at one end of said bracket spaced 100 13 project, a rock-shaft 14 being disposed vertically in said ears. The work-holder is supported on the shaft 14 by a bar 105

15 rigid with said shaft, and to the forward end of said bar the work-supporting plate 16 is secured, the latter having a needle-opening 16'. A bar 17 is formed with an upwardly projecting tongue 17' and has a depending lug 18 which is pivoted on a horizontal axis to an upward extension 19 of the bar 15. An upper button-clamp supporting bar 20 is slidably mounted on the bar 17 and 10 has a groove 20' into which the tongue 17' fits (Fig. 5). The bar 20 is held on bar 17 by a plate 21 and securing screws 22 passing through said plate and into an upper extension of the tongue 17' fitting into the slot 23 15 in bar 20. The bar 20 and its supported button-clamp are longitudinally shifted by a lever 24 fulcrumed on the plate 21 by a screw 25, the outer end of the lever having a slot 26 through which passes a screw 27 secured to the bar 20. Stop-pins 28 projecting from the bar 20 on each side of the lever 24 limit the movement of the latter in either direction. Means are provided for varying the throw of lever 24, said means comprising a 20 wedge-shaped plate 29 slidably secured to the lever by a screw 30 passing through a slot 31 in the plate and threaded into the lever (Fig. 7). The free end of lever 24 has an upturned portion 32 and the corresponding end of the plate 29 has an upturned portion 33. A thumb-screw 34 is rotatably secured in the portion 32 and screw-threaded into the portion 33, a lock-nut 35 being provided for securing the screw 34 in adjusted 25 position. It will be seen that by rotation of the screw 34 the plate 29 may be advanced or retracted between the stop-pins 28 to variably limit the throw of lever 24. Pivotally attached to the bar 20 by screws 36 are 30 the usual button-clamping levers 37, the downwardly bent forward ends of which are turned inwardly and notched to hold a button 38. The levers 37 carry downwardly projecting pins 39 which enter the rearwardly converging slots 40 in a slide-plate 41 carried by a slide-bar 42, which bar is confined to slide lengthwise on the bar 20 by screws 43 and 44 which pass downwardly through the slot 23 in bar 20 and are threaded into the slide-bar 42. The slide-bar 42 is 35 formed with the usual button-centering stop 45, and is urged forward by a coil spring 46 secured to the screw 43 and to a pin 47 on a bracket 48 mounted on bar 20. As the slide-bar moves forwardly it causes the jaws of levers 37 to close on a button inserted therebetween. Secured to the under side of each lever 37 is a spring-plate 49 which extends forwardly beneath the button to press the 40 latter upwardly and hold it against vertical movement. A screw 50 projects from the bracket 48 and a link 51 extends between said screw and a collar 52 secured on the presser-bar 53. A presser-lifting lever 53' 45 is adapted to engage a lug on the collar 52

to lift the presser-bar and its connected button-clamp. The slide-bar 42 is moved rearwardly to open the button-clamping levers 37 by a slotted finger-lever 54 fulcrumed on the bar 20 and bearing against the screw 43, 70 said lever being held in adjusted position by a set-screw 55 passing through the slot in the lever and threaded into the plate 20.

Between the ears 13 an arm 56 is attached to the rock-shaft 14 by a collar and set-screw (Figs. 4 and 5). A slide-block 57 is mounted on the arm 56, and is moved in either direction by a thumb-screw 58 rotatably secured in a lug 59 on the arm 56 and threaded into said block. A link 60 is pivotally secured at one end to the arm 56 and block 57 by a bolt 61 which passes loosely through the block and through a segmental slot 62 in the arm. A spring 63 surrounding bolt 61 and a nut 64 on the bolt serve to retain the link, slide-block and arm in engagement (Fig. 9). The link 60 is pivotally secured at 60' to a rocker-arm 65 fulcrumed on the bracket 12 at 66. The rocker-arm carries a cam-roller which travels in a groove 90 on a cam 67, which latter has a geared one-to-two connection with the main-shaft 9.

The overhanging arm 2 has a projecting lug 68 at its rear end to which is secured a hinge member comprising a sheet-metal disk 69 having an offset arm 70 which has a downwardly bent front portion 71. A similar disk 72 has an offset arm 73 having a downwardly bent rear portion 74. The bent portions 71 and 74 are pivotally connected by a screw 75. A curved bracket-arm 76 is secured to the disk 72 and has at its free end an enlargement 77 with a hub 78, in which is secured by a set-screw 79 a spool-pin 80, to the other end of which is 105 secured a spool retaining disk 81. When not in use or in shipping the spool-holder may be readily turned down out of the way, as shown in dotted lines in Fig. 1.

When sewing a two-hole button the wedge-shaped part 29 is advanced until it is in contact with both the stop-pins 28, which locks the button-positioning means against lengthwise shifting. The work having been placed in position and the machine 115 started, the cam 67 on the main-shaft operates through the connections 65, 60, 56 to rock the shaft 14, which oscillates or jogs the entire work-holder to present first one and then the other of the holes in the button to the needle. In the case of a four-hole button the part 29 is retracted until when the lever 24 is moved against one of the stop-pins 28 a pair of holes in the button are in alignment with the needle. After 120 sufficient stitches have been laid in this pair of holes by the jogging movement of the work-holder, the lever 24 is moved against the other stop-pin 28, thereby shifting the reciprocating button-positioning means to 125 130

bring the other pair of holes into stitching relation with the needle. By means of the thumb-screw 58 the oscillatory or jogging movement of the work-holder and its button-positioning means may be varied to suit different spacings of the holes in the buttons, and due to the fact that the segmental slot 62 has as its center the pivotal point of the link 60, the adjustment is self-centering, that is, in all adjustments the needle is midway between the extremes of oscillation. By means of the thumb-screw 34 the longitudinal shifting movement of the button-positioning means may also be varied for different spacings of the holes in the buttons, and due to the symmetrical disposition of the lever 24 and its wedge-shaped plate 29 with respect to the stop-pins 28, this adjustment is also self-centering. By making the support for the work-holder independent of the cloth-plate and disposing it outside of the periphery of said plate, access to the mechanism below the cloth-plate may be readily had by merely removing the screws securing the plate and sliding the latter to one side.

Having thus set forth the nature of the invention, what I claim herein is:

1. In a sewing machine, in combination, a frame including a base and an overhanging bracket-arm rising therefrom, a cloth-plate supported by said base and covering the same, stitch-forming mechanism incorporated in said frame and including a reciprocating needle and complemental loop-taking means supported at opposite sides of said cloth-plate, and an oscillatory work-holder including button-positioning means carried by said base and mounted thereon below and independently of said cloth-plate and positioned mainly above the plane of the latter, whereby the cloth-plate may be removed without dismounting the work-holder.

2. In a sewing machine, in combination, a frame including a base and an overhanging bracket-arm rising therefrom, a cloth-plate supported by said base and covering the same, stitch-forming mechanism incorporated in said frame and including a reciprocating needle and complemental loop-taking means supported at opposite sides of said cloth-plate, an oscillatory work-holder including button-positioning means pivotally carried by said base and mounted thereon below and independently of said cloth-plate and positioned mainly above the plane of the latter, and operating mechanism for the work-holder disposed entirely below said cloth-plate.

3. In a sewing machine, a cloth-plate, stitch-forming mechanism on opposite sides thereof, a work-holder including button-positioning means, a support therefor independent of said cloth-plate, means for jog-

ging said support and work-holder, means carried by said work-holder for longitudinally shifting said button-positioning means, and means carried by the latter for limiting said shifting movement.

4. In a button sewing machine, a cloth-plate, stitch-forming mechanism on opposite sides thereof, a work-holder including button-positioning means, a support therefor independent of said cloth-plate, means for jogging said work-holder, means for longitudinally shifting said button-positioning means, and means carried by said shifting means and the button-positioning means for variably limiting the longitudinal movement of the latter.

5. In a sewing machine, a base, a removable cloth-plate covering the base, stitch-forming means on opposite sides of said plate, a work-holder independent of said plate, and means secured to the base below the cloth-plate and located outside of the periphery of said plate for supporting and actuating said work-holder.

6. In a button sewing attachment for sewing machines, a support, adjustable means for jogging said support, a member pivotally mounted on said support, button-positioning means carried by said member, a lever for shifting said button-positioning means, fixed stops therefor, and unitary means carried by the lever and cooperating with the stops for varying the throw of said lever in either direction.

7. In a button sewing machine, button-positioning means, a lever for shifting the same, and means for variably limiting the throw of said lever, comprising stops and an adjustable member having inclined faces adapted to engage said stops.

8. In a button sewing attachment for sewing machines, a pivoted member, button-positioning means carried thereby, and means for shifting the latter comprising a lever fulcrumed on said member and connected to said button-positioning means, fixed stops on each side of said lever, and inclined means adjustably carried by said lever for varying its throw.

9. In a sewing machine, a cloth-plate, stitch-forming mechanism on opposite sides of said plate, a rock-shaft supported independently of said plate, a work-holder carried by said shaft, a slotted arm fixed to said shaft, a link having a projection entering said slot, means for actuating said link, and means mounted on said arm for varying the location of said projection in said slot.

10. In a button sewing machine, stitch-forming mechanism including a needle, a work-holder including button-positioning means, a lever carried by said work-holder adapted for longitudinally shifting said button-positioning means in opposite directions

and coacting means carried by said lever and the button-positioning means for variably limiting the movements of the latter.

11. In a button sewing machine, stitch-forming mechanism including a needle, manual means for shifting a button in opposite directions in a path symmetrically disposed with respect to said needle, and an adjustable element carried by said first 10 means for varying the length of said path while maintaining the path in symmetrical relation to said needle.

12. In a button sewing machine, a cloth-plate, stitch-forming mechanism disposed on 15 opposite sides thereof, a rock-shaft disposed outside the periphery of said plate, a work-holder including button-positioning means carried by said rock-shaft above the cloth-plate, means carried by the work-holder for shifting said button-positioning 20 means, means below the cloth-plate for oscil-

lating said shaft and its supported work-holder, and means carried by said shaft for varying the degree of oscillation.

13. In a button sewing machine, in combination, stitch-forming mechanism including a reciprocating needle, a work-holder, automatic means for relatively jogging the stitch-forming mechanism and work-holder laterally of the needle to sew 30 through two holes of a four-hole button, and manually operated means for producing a predetermined shift of the work-holder transversely of the direction of said relative jogging movements, said manually operated 35 means embodying a single adjustable device for limiting such shift in either direction while maintaining it symmetrical with respect to the needle.

In testimony whereof, I have signed my 40 name to this specification.

WILLIAM L. BARRON.
